Primary Examiner — Andrew Kerr*Assistant Examiner* — Chariton Alexakis(74) *Attorney, Agent, or Firm* — Jose Cherson Weissbrot(57) **CLAIM**

The ornamental design for a crown shaped lid, as shown and described.

DESCRIPTION

FIG. 1 is a perspective view of a crown shaped lid showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front view of a crown shaped lid showing in use view.

Broken lines in the drawings depict portions of the crown shaped lid that form no part of the claimed design.

1 Claim, 8 Drawing Sheets(56)
